UNITED STATES PATENT OFFICE.

JOSHUA HOLDSWORTH, OF CENTERDALE, RHODE ISLAND.

WINDING-MACHINE.

No. 801,011.

Specification of Letters Patent.

Patented Oct. 3, 1905.

Application filed December 1, 1904. Serial No. 235,038.

To all whom it may concern:

Be it known that I, JOSHUA HOLDSWORTH, a citizen of the United States, residing at Centerdale, in the county of Providence and State 5 of Rhode Island, have invented a new and useful Improvement in Winding-Machines, of which the following is a specification.

This invention has reference to an improvement in winding-machines, and more particularly to an improvement in jack-spool-filling machines.

In the process of preparing warp-threads for the warp-beam of a loom the threads are wound on a jack-spool from a creel and from 15 a plurality of jack-spools onto the warp-beam of a loom. In winding the threads on the jack-spool from the creel each thread is reciprocated so as to occupy a space of three-quarters of an inch on the jack-spool—that is to 20 say, a jack-spool thirty-nine inches long between ends will hold fifty-two threads. In winding the threads on the jack-spool from the creel a thread is liable to break or an imperfect thread may be wound on the spool.

25 In the breaking of a thread it has heretofore been the practice to tie the broken thread, break all the other threads, wind the first thread to a level with the adjacent threads, tie all the broken threads, and then proceed 30 with the winding of all the threads. This method of overcoming the difficulty is slow and detrimental in the weave, as the ties or knots of the broken threads all come together on the jack-spool. This method is also used 35 in the replacing of an imperfect thread with a perfect thread.

The object of my invention is to give a more perfect winding to the warp-threads on a jack-spool than has heretofore been done, and I 40 accomplish this object by the use of my improved jack-spool-filling machine, whereby a cavity in the threads on the jack-spool caused by the breaking of a thread or the removal of an imperfect thread is filled without the breaking 45 of all the threads.

My invention consists in the peculiar and novel construction of a jack-spool-filling machine adapted to fill a cavity in the threads on a filled jack-spool caused by the breaking of 50 a thread or the removal of an imperfect thread, said machine consisting of a frame, front, back, and end rails forming a part of the frame, cross-struts adjustably secured to the front and back rails, bearings adjustably secured to the cross-struts adapted to hold a 55 jack-spool, a supporting-frame adjustably se-

cured to the front rail, bearings in the supporting-frame adapted to hold a driving-pulley and a spindle, means for revolving the driving-pulley, means on the spindle for holding a spool, a belt connecting the driving-pulley with a pulley on the spindle, a two-part circular frame the upper half of which is rigidly secured to the supporting-frame, a two-part ring-pulley, means for rotatably securing the two-part ring-pulley in the two-part circular frame, means for opening the two-part circular frame and ring-pulley to receive a jack-spool, a belt connecting the driving-pulley with the ring-pulley, a pin on the two-part ring-pulley adapted to hold a spool of warp-thread, a tension device on the ring-pulley, a reciprocating thread-guide on the ring-pulley, and other details of construction, whereby the spool of warp-thread on the ring-pulley is revolved around the stationary jack-spool and through the reciprocating thread-guide fills the cavity in the thread on the jack-spool with thread from the spool on the ring-pulley, as will be more fully set forth herein- 75 after.

Figure 1 is a top plan view of my improved jack-spool-filling machine, showing the means for supporting the jack-spool in the machine, the two-part circular frame and ring-pulley 85 surrounding the jack-spool, and the spool of warp-thread on the ring-pulley in a position to fill a cavity in the threads on the warp-beam, said threads and cavity being indicated in broken lines. Fig. 2 is a vertical view of 90 the machine looking at the front, showing the means for adjustably securing the cross-struts and the supporting-frame to the front rail of the machine. Fig. 3 is an enlarged detail transverse sectional view taken on line W W 95 of Fig. 2, showing the supporting-frame adjustably secured to the front rail, the upper half of the two-part circular frame rigidly secured to the supporting-frame, the two-part ring-pulley in the two-part circular 100 frame in the position for opening the frame and pulley, the spool, tension device, and reciprocating thread-guide on the two-part ring-pulley, and the lower half of the circular frame and ring-pulley in the lowered or 105 open position to receive the jack-spool, in broken lines. Fig. 4 is a detail sectional view taken on line X X of Fig. 3, showing the construction of the two-part circular frame and the two-part ring-pulley in the frame. Fig. 110 5 is a still further enlarged detail face view of part of the two-part circular frame and

ring-pulley, showing the spool of warp-thread, the tension device, and the automatic reciprocating thread-guide on the two-part ring-pulley; and Fig. 6 is an enlarged detail 5 sectional view taken on line X X of Fig. 3, showing the means for holding the two-part ring-pulley from rotating in the circular frame when the frame and pulley are opened to receive the jack-spool.

10 In the drawings, *a* indicates the frame of the machine; *b b*, the cross-struts; *c*, the supporting-frame; *d*, the driving-pulley; *e*, a spindle; *f*, a belt; *g*, a two-part circular frame; *h*, a two-part ring-pulley; *i*, a belt; *k*, a spool; *l*, a tension device; *m*, an automatic thread-guide; *o*, a jack-spool, and *p* a warp-thread.

The frame *a* consists of the four legs *a' a'*, the front rail *a²*, the back rail *a³*, and the end rails *a⁴ a⁴*, secured at their ends to the upper 20 part of the legs to form a rectangular frame, as shown in Fig. 1. The cross-struts *b b* are secured at each end to the fittings *b' b'*, which in turn are adjustably secured to the front and back rails by the set-bolts *b² b²*, as shown 25 in Fig. 2. The bearings *b³ b³* each have a slot *b⁴* for the shaft of the jack-spool and are adjustably secured to the cross-struts *b b* by a set-bolt *b⁵*, as shown in Fig. 4. By this construction the cross-struts *b b* are adjusted 30 lengthwise on the front and back rails for different lengths of jack-spoons and the jack-spool adjusted on the struts for centering the same. The supporting-frame *c* is adjustably secured to the front rail *a²* by the set-bolt *c'* 35 and has the upwardly-extending member *c²*, in which is the bearing *c³* for the driving-pulley *d* and the bearing *c⁴* for the spindle *e*. The arm *c⁵* extends outward from the back of the frame *c* for rigidly supporting the fixed 40 half of the two-part circular frame *g*, as shown in Figs. 1 and 3. The front rail *a²* extends through an opening in the frame *c*, which approximately fits the rail.

The driving-pulley *d* has the handle *d'*. It 45 is grooved for the belts *f* and *i* and is rotatably secured to the bearing *c³* by the shaft-bolt *d²*. The spindle *e* is rotatably secured in the bearing *c⁴* and has the grooved pulley *e'* for the belt *f*, which connects the pulley *e'* 50 with the driving-pulley *d*, as shown in Fig. 3. A spool *k* may be secured to the spindle *e* by friction or other well-known means.

The two-part circular frame *g* consists of 55 two semicircular segments, each segment forming one-half of a two-part circular ring. The fixed upper segment *g'* has the arm *g²* rigidly secured to the arm *c⁵* of the frame *c* by the bolts *g³ g³*, the forked lugs *g⁴*, and the screw-threaded transverse hole *g⁵* for the 60 thumb-screw *g⁶*. The lower movable segment *g⁷* is pivotally secured at its lower end to the fixed segment *g'* by the hinge *g⁸* and has the lug *g⁹* on its upper end. The locking-bolt *g¹⁰* is pivotally secured at one end to the lug *g⁹* 65 and has the thumb-nut *g¹¹* adapted to engage

with the forked lug *g⁴* on the upper fixed segment *g'* and firmly hold the lower movable segment in the closed position, as shown in full lines in Fig. 3. Each segment forming the two-part circular frame *g* has the groove *g¹²* in its inner circumference, which when the two segments are secured together forms a continuous groove.

The two-part ring-pulley *h* consists of two semicircular segments *h'* and *h²*, each segment 75 forming one-half of a two-part ring, the break in the ring-pulley coinciding with the break in the circular frame *g*. The segment *h'* has the transverse hole *h³* and the boss *h⁴* supporting the pin *h⁵* on the side of the ring-pulley. The spool *k*, filled with the warp-thread *p*, is rotatably secured on the pin *h⁵* by a spring-pressed point on the spool engaging with a groove in the end of the pin, as shown in broken lines in Fig. 5, or any other 80 well-known means. Both segments of the ring-pulley have the lip *h⁶* forming a continuous circular lip shaped to fit the circular groove *g¹²* in the frame *g*, and the V-shaped circular groove *h⁷* for the belt *i*.

The tension device *l* consists of the flat metal spring *l'*, secured to the side of the ring-pulley *h* by the screws *l²*. The free end *l³* is in frictional contact with the end of the spool *k*, as shown in Fig. 5.

The automatic thread-guide *m* consists of the flat metal guide-arm *m'*, having the eyes *m² m²* in each end. This arm is pivotally secured adjacent one end to the bracket *m³* by the screw *m⁴* and is limited in its movement 100 by the stop *m⁵* on the bracket. The bracket *m³* is rigidly secured to the side of the ring-pulley *h* in a position to bring the longer end of the arm *m'* adjacent the spool *k*. The warp-thread *p* is threaded from the spool *k* 105 through the eyes *m² m²* in the arm *m'*. As the thread unwinds from the spool it automatically reciprocates the guide-arm *m'*, as shown in full and broken lines in Fig. 5, thus reciprocating the thread on the jack-spool to 110 fill a cavity in the threads on the jack-spool, as indicated in broken lines in Fig. 1.

In the use of my improved jack-spool-filling machine a jack-spool is filled with warp-threads from the creel in the usual way. 115 After the jack-spool is filled it may be found that a thread is broken or an imperfect thread may have to be removed, leaving a cavity in the threads on the jack-spool to be filled by a perfect warp-thread. In the operation of my machine for this purpose the ring-pulley *h* is revolved until the break in the ring-pulley *h* coincides with the break in the circular frame *g* with the segment *h'* at the top, when the thumb-screw *g⁶* is screwed through the fixed segment *g'* into the hole *h³* in the ring-pulley, thus securing the segment *h'* of the ring-pulley to the fixed segment *g'* of the circular frame *g*. The ring-pulley and circular frame are now opened to receive the jack-spool by 120 125 130

- removing the belt i , unlocking the locking-bolt g^{10} , and dropping the lower segments of the circular frame and ring-pulley into the position as shown in broken lines in Fig. 3.
- 5 The jack-spool is now placed in the bearings $b^3 b^3$ on the cross-struts $b b$, the frame g , with the ring-pulley h , closed and locked by the locking-bolt g^{10} , and the thumb-screw g^6 removed from the hole h^3 in the ring-pulley.
- 10 An empty spool k is now placed on the spindle e and filled with a warp-thread from a bobbin held by the operator by turning the driving-pulley d by the handle d' . The filled spool is now removed from the spindle e , placed on the pin h^5 on the ring-pulley h , and the thread threaded through the thread-guide m to the thread-cavity in the jack-spool. The supporting-frame c is now adjusted on the front rail a^2 to bring the thread in the correct position
- 15 20 on the jack-spool, the belt i connecting the driving-pulley d with the ring-pulley h replaced and the pulley d revolved by the handle d' in the direction of the arrow, as shown in Fig. 3. This revolves the ring-pulley h (through the belt i) and the spool k , having the warp-thread p , around the jack-spool in the direction of the arrow on the ring-pulley. The warp-thread p is wound on the jack-spool and through the automatic thread-guide m is given a reciprocating motion on the jack-spool and fills the cavity to the level of the adjacent threads.
- 25 It is evident that one of the cross-struts $b b$ could be dispensed with and a bearing b^3 adjustably secured to an end rail a^4 , if desired, without materially affecting the spirit of my invention.

Having thus described my invention, I claim as new and desire to secure by Letters Patent—

- 40 1. In a jack-spool-filling machine, a frame, means for supporting a jack-spool in the frame, means for rotatably supporting a spool of warp-thread, and means for revolving the spool of warp-thread around the jack-spool to wind the warp-thread on the jack-spool, as described.
2. In a jack-spool-filling machine, a frame, means for adjustably supporting a jack-spool in the frame, a two-part circular frame, a two-part ring-pulley, means for rotatably securing the ring-pulley in the circular frame, means for adjustably securing the circular frame to the frame of the machine, and means for revolving the ring-pulley to revolve a spool of warp-thread carried by the same around the jack-spool to wind the thread on the jack-spool, as described.
3. In a jack-spool-filling machine, a frame, means for adjustably supporting a jack-spool on the frame, a two-part circular frame, a two-part ring-pulley, means for rotatably securing the ring-pulley in the circular frame, means for opening the circular frame and ring-pulley to receive the jack-spool, means for adjustably securing the circular frame to the
- 45 50 55 60 65 70 75 80 85 90 95 100 105 110 115 120 125 130
- frame of the machine, and means for revolving the ring-pulley to revolve a spool of warp-thread carried by the same around the jack-spool to wind the thread on the jack-spool, as described.
4. In a jack-spool-filling machine, a frame, means for adjustably supporting a jack-spool on the frame, a two-part circular frame, a two-part ring-pulley, means for rotatably securing the ring-pulley in the circular frame, means for opening the circular frame and ring-pulley to receive the jack-spool, a supporting-frame adjustably secured to the frame of the machine, means for rigidly securing one-half of the two-part circular frame to the supporting-frame, a spindle, means on the supporting-frame for rotatably supporting the spindle, means for revolving the spindle, and means for revolving the ring-pulley to revolve a spool of warp-thread carried by the same around the jack-spool to wind the thread on the jack-spool, as described.
5. A jack-spool-filling machine consisting of a frame having front, back and end rails, cross-struts adjustably secured to the front and back rails, bearings adjustably secured to the cross-struts adapted to hold a jack-spool, a supporting-frame adjustably secured to the front rail, a driving-pulley, a spindle, a pulley on the spindle, bearings on the supporting-frame adapted to support the driving-pulley and the spindle, means for driving the driving-pulley, a belt connecting the driving-pulley with the spindle-pulley, a two-part circular frame, means for rigidly securing one part of the circular frame to the supporting-frame, a two-part ring-pulley, means for rotatably securing the ring-pulley in the circular frame, means for opening the circular frame and ring-pulley to receive the jack-spool, a belt connecting the driving-pulley with the ring-pulley, a pin on the ring-pulley adapted to hold a spool of warp-thread, a spring tension device on the ring-pulley acting on the spool, and an automatic thread-guide on the ring-pulley consisting of a pivoted arm with eyes for the thread, as described.
6. In a jack-spool-filling machine, the combination with the supporting-frame c , the driving-pulley d , and means for driving the pulley d , of the two-part circular frame g consisting of the semicircular segment g' having the arm g^2 secured to the supporting-frame c , the forked lug g^4 , the thumb-screw g^6 in screw-thread engagement with the segment, the semicircular segment g^7 pivotally secured to the segment g' by the hinge g^8 and having the lug g^9 , and the locking-bolt g^{10} pivotally secured to the lug and having the thumb-nut g^{11} , both segments having the internal groove g^{12} ; the two-part ring-pulley h consisting of the semicircular segments h' and h^3 , the segment h' having the transverse hole h^3 , and the pin h^5 , both segments having the lip h^6 shaped to fit the groove g^{12} in the circular frame g and

the V-shaped groove h^7 , and the belt i connecting the driving-pulley d with the ring-pulley h , as described.

7. In a jack-spool-filling machine, the combination with the ring-pulley h having the boss h^4 and pin h^5 , of the tension device l consisting of the flat spring l' secured to the ring-pulley h by the screws l^2 , the free end l^3 being in frictional contact with the end of the spool h , the automatic thread-guide m consisting of the arm m' having the eyes $m^2 m^3$, the bracket m^3 , the screw m^4 for pivotally securing the arm to the bracket, the stop m^5 on the bracket, and means for securing the bracket to the ring-pulley h , as described.
8. In a jack-spool-filling machine, the combination of the frame a , the adjustable cross-struts b , the adjustable bearings $b^3 b^3$ on the cross-struts, a supporting-frame c , a driving-pulley d , a spindle e , bearings on the support-

ing-frame c for the driving-pulley d and the spindle e , a pulley on the spindle, a belt f connecting the driving-pulley with the spindle-pulley, a two-part circular frame g , means for opening the circular frame, a two-part ring-pulley h , means for rotatably securing the ring-pulley in the circular frame, means for rigidly securing one part of the circular frame to the supporting-frame, a belt i connecting the driving-pulley with the ring-pulley, a tension device l on the ring-pulley, and an automatic thread-guide m on the ring-pulley, as described.

In testimony whereof I have signed my name to this specification in the presence of two subscribing witnesses.

JOSHUA HOLDSWORTH.
